DESIGN FOR A KNOB FOR AN ELECTRIC SWITCH

Edwin W. Landmeier, Cincinnati, Ohio, assignor
to The Wadsworth Electric Mfg. Co., Inc., Cov-
ington, Ky., a corporation of Kentucky

Application March 20, 1941, Serial No. 99,739

Term of patent 14 years

To all whom it may concern:

Be it known that I, Edwin W. Landmeier, a citizen of the United States, residing at Cincinnati, in the county of Hamilton and State of Ohio, have invented a new, original, and ornamental Design for a Knob for an Electric Switch, of which the following is a specification, reference being had to the accompanying drawing, forming a part thereof.

Figure 1 is a perspective view of a knob for an electric switch showing my new design.

Figure 2 is a top plan view.

Figure 3 is an end elevation.

I claim:

The ornamental design for a knob for an electric switch, substantially as shown.

EDWIN W. LANDMEIER.
